UNITED STATES PATENT OFFICE.

CARL MARTINI, OF BERLIN, GERMANY, ASSIGNOR TO MARTINI & HÜNEKE
MASCHINENBAU-AKTIEN-GESELLSCHAFT, OF BERLIN, GERMANY, A CORPO-
RATION OF GERMANY.

DEVICE FOR SAFELY STORING INFLAMMABLE LIQUIDS.

1,520,758.

Specification of Letters Patent.

Patented May 7, 1912.

Application filed February 3, 1912. Serial No. 675,236.

To all whom it may concern:

Be it known that I, CARL MARTINI, a subject of the German Emperor, and resident of Berlin, Germany, have invented certain new and useful Improvements in Devices for Safely Storing Inflammable Liquids, of which the following is a specification.

My invention relates to devices for safely storing gasoline, and other inflammable liquids and has for its object to combine a construction in which provision is made for guarding against the danger resulting from leaks or breaks in the conveying pipes, with means for raising or propelling the liquid to the place of withdrawal or use, through the medium of a pump working with the assistance of a relatively heavy pressure liquid (inert or neutral liquid).

A specific embodiment of my invention is shown in the accompanying drawing, which is a diagrammatic elevation, with parts in section.

In this particular construction, the gasoline or other inflammable liquid *f* is contained in a receptacle 1, closed except as to the pipe connections specified hereinafter. The cover 2 carries the gasoline delivery pipe 3, which leads to the place of consumption or withdrawal, for instance the draw faucet 4. This faucet and the delivery pipe are surrounded by a jacket 5 properly spaced from said pipe and faucet. The annular jacket space does not communicate with the interior of the receptacle 1.

The neutral or inert liquid *n* (which should be heavier than the liquid *f*) is contained, for instance, in an open receptacle 6, from the lower part of which a suction pipe 7 leads to the liquid-conveying pump 8 (of any suitable construction), the delivery pipe 9 of this pump leading into the receptacle 1, through its cover 2. The suction pipe 7 of the pump 8 is connected by a branch pipe 10 with the chamber surrounded by the jacket 5 of the delivery pipe 3, at any suitable point.

The liquid *n* should be inert, that is to say, it should have no action on the inflammable liquid *f*; in the case of gasoline, the inert liquid *n* may be water.

In the operation of the device described above the pump 8 will draw some inert liquid *n* from the receptacle 6 through the

pipe 7 and will force it into the receptacle 1 through the pipe 9. Since the inert liquid *n* is heavier than the inflammable liquid *f*, the latter will float on top, and thus the transfer of inert liquid to the receptacle 1, which originally is full of inflammable liquid, will cause the inflammable liquid to be forced into the delivery pipe 3, so as to reach the faucet 4 or other place of use. During this operation the branch pipe 10, communicating with the suction pipe 7, will become filled with inert liquid up to the level of the suction valve or suction port of the pump 8.

Should a break or leak occur at any point of the jacket 5, air will enter at such point into the space between the jacket 5 and the delivery pipe 3, and such air will pass into the branch pipe 10 and into the suction pipe 7 communicating therewith. This will interrupt almost immediately the conveying action of the pump 8, so that no further supply of inert liquid *n* will be drawn from the receptacle 6 and transferred to the receptacle 1 through the pipe 9. The raising of the inflammable liquid *f* in the delivery pipe 3 will therefore also be interrupted. Thus no inflammable liquid *f* can escape through the leak or break in the jacket 5, even if the delivery pipe should be injured at the same point; in this latter case, any liquid escaping from the pipe 3 will trickle down on the outside of the pipe and collect above the cover 2, between the jacket and the pipe.

It will be understood that I do not restrict myself to the specific construction shown, as various modifications may be made without departing from the nature of my invention as set forth in the appended claims.

I claim:

1. A device for the safe storage of inflammable liquids, comprising a closed receptacle for the inflammable liquid, a delivery pipe leading therefrom, a receptacle for an inert liquid, a pump provided with a suction pipe connected with the last-named receptacle and with a delivery pipe leading to the first-named receptacle, a jacket surrounding the delivery pipe for the inflammable liquid and forming therewith a space shut off from the interior of the closed re-

ceptacle, and a permanently open connection from the said space to the said suction pipe.

2. A device for the safe storage of inflammable liquids, comprising a closed receptacle for the inflammable liquid, a delivery pipe leading therefrom, a pump having a suction pipe connected with a supply of an inert liquid, and a delivery pipe leading to said receptacle, a jacket surrounding the delivery pipe for the inflammable liquid and

forming therewith a space shut off from the interior of said receptacle but communicating with said suction pipe.

In testimony whereof I have signed this 15 specification in the presence of two subscribing witnesses.

CARL MARTINI.
